MULTIPLE CONTACT ASSEMBLY
John E. Taylor, Jr., 413 Pine Ave.,
Waynesboro, Va. 22980
Filed Jan. 12, 1966, Ser. No. 520,104
5 Claims. (Cl. 339—18)

ABSTRACT OF THE DISCLOSURE

A multiple contact assembly for bringing contacts on a fixed assembly panel into engagement with contacts on a movable assembly panel. The two panels are first positioned with respect to one another by a hanger arrangement on one of the panels. In this position the movable panel is operatively related to a cam arrangement which when actuated initially causes vertical and horizontal displacement of the contacts of the movable panel while engaging the fixed panel's contacts, followed by a limited reverse vertical and horizontal displacement thereof. This action produces double wiping of the contacts to achieve positive electrical connections.

The present invention relates to a multiple contact assembly and, more particularly, to a structural arrangement for insuring good electrical connections between the tips of patchcords and the multiple contacts.

It is known to provide a fixed panel member having a number of contacts associated therewith, the contacts being joined to electrical circuitry as desired. In order to interconnect various circuitry, patchcords are selectively connected to appropriate contacts to complete electrical paths between the circuit elements. There has been developed an arrangement for simultaneously interconnecting a number of circuits by providing a movable panel member having apertures therein corresponding in position to the respective locations of the contacts in the fixed panel member. Patchcords are selectively inserted in the apertures such that their tips project towards the fixed contacts. The movable panel is then moved towards the fixed panel whereby the patchcord tips engage their respective contacts to complete the electrical paths.

Known multiple contact assemblies suffer the deficiency of having imperfect electrical connections between the patchcord tips and their associated contacts due to the presence of foreign particles and lack of positive contact between the cord tips and the contact elements. This results in unreliable circuit operation which is extremely difficult to trace.

The present invention overcomes the foregoing deficiency by providing an improved structure for assuring positive electrical connections.

An additional object of the invention is to provide a multiple contact assembly which is less sensitive to the effects of shock and vibration which tend to open the individual electrical contacts and also separate the fixed and movable panel members.

Further objects and the entire scope of the invention will become more fully apparent when considered in light of the following detailed description of an illustrative embodiment of the invention and from the appended claims.

The illustrative embodiment may be best understood by reference to the accompanying drawings, wherein:

FIGURE 1 is a view in perspective of the multiple contact assembly, the fixed and movable panels being separated for convenience of illustration;

FIGURE 2 is an enlarged fragmentary view taken along line 2—2 of FIGURE 1; and

FIGURE 3A-D is a diagrammatic representation of the relationship between a patchcord tip and a contact

2

as the movable assembly panel is moved into operative relationship with the fixed panel.

Briefly, the invention comprises an arrangement wherein the movable assembly panel is manually positioned on hangers associated with the fixed panel. The hangers are provided with spring-loaded latching members for positively locating the movable panel as it rests on the hangers such that the bottom of the movable panel is in operative relationship with respect to a cam shaft. As the cam shaft is rotated, the movable panel is displaced upwardly and inwardly toward the fixed panel such that patchcord tips projecting from the movable panel engages associated paddle contacts on the fixed panel. During the initial engagement with the contacts, the cord tips rub along the contacts in one direction while forcing the resilient contacts upwardly. The rotation of the cam shaft is continued beyond the maximum rise of the cam such that the movable panel begins to move downwardly and outwardly with respect to the fixed panel. Since the resilient contacts are pressed against their associated patchcord tips, the latter rub the contacts in the opposite direction until cam rotation is stopped. By this double rubbing or wiping action, the contact and patchcord tip surfaces are cleaned thereby insuring positive electrical connections between the cord tips and the contacts.

Now that the invention has been briefly outlined, an illustrative embodiment thereof will be described. Referring to FIGURE 1, there is illustrated a multiple contact assembly comprising a movable panel 10 and a fixed panel 12. The movable panel comprises a rectangular frame 14 supporting a plurality of insulator blocks 16 having spaced apertures 18 therein. Handles 20 are mounted at the opposite ends of frame 14 to facilitate manual manipulation of the movable panel. A pair of rotatable bearing elements 22 project outwardly from each end of frame 14, the axes of rotation of these bearings being in the plane of said frame.

The fixed panel 12 comprises a rectangular frame portion 24 which supports a contact assembly including a plurality of spaced contacts projecting through insulating material 26 such that contacts are insulated from one another. Each contact has a portion 28 extending forwardly of insulator 26 (FIGURE 3), which portion forms a conventional resilient paddle contact, and a rearwardly projecting portion (not shown) on the opposite side of insulator 26 to which suitable electrical circuits may be connected. A pair of vertical support members 30 and 32 are suitably joined to the ends of frame 24 and project forwardly of and below said frame. Each support member is provided with a pair of recesses intermediate the ends thereof to receive identical hanger elements 34. The structural details of the hanger elements will be described hereinafter with respect to FIGURE 2. The lower ends of support members 30 and 32 are bored forwardly of frame 24 to rotatably receive a shaft 36. To facilitate rotation of shaft 36, suitable bearings may be provided in the support members. The shaft 36 is also rotatably supported intermediate its ends by a suitable journal element 38 attached to the bottom of frame 24. A plurality of identical cam elements 40 are attached along shaft 36 for rotation therewith. The rise and fall portions of the cams 40 are positioned in alignment. A portion of shaft 36 projects through support member 30 and is attached to a member 42 whereby actuation of said member rotates the shaft and the cams 40 attached thereto. A housing 44 is attached to the outer surface of support member 30. Housing 44 is provided with a recess 46 for receiving a portion of the cam actuator member 42 in its fully closed position. A conventional spring-loaded detent 48 is provided in housing 44 within the recess 46. This detent is positioned to project into a cavity 50 machined in

a shoulder 52 of the cam actuator 42 to lock said actuator in its fully closed position.

Referring now to FIGURE 2, the structure of one of the identical hanger elements 34 will be described. The support member 30 is provided with a recess 54 which receives hanger 34. The hanger is secured to support 30 by suitable means such as screws 56. The hanger comprises two integral portions 58 and 60, the former portion being received within recess 54 while portion 60 projects beyond the support member 30 away from frame 24. Portion 60 is machined at its top surface rearwardly of its forwardmost portion to provide a level shelf 62 thereon. The shelf projects rearwardly into portion 58 to meet a contiguous machined channel 64 inclined upwardly and inwardly towards the frame 24. The planar surface of hanger portion 58 which abuts the support member 30 at the bottom of recess 54 is provided with a cavity 66, which communicates with shelf 62 and channel 64, and within which a latch element 68 is pivotally mounted. The latch element is formed at its upper surface, rearwardly of its forward tip 70, with a depression 72 having substantially the same curve as bearing elements 22. A bore hole 74 is also machined in hanger portion 58 to communicate with cavity 66. A compression spring 76 is suitably held in bore 74 to force a plunger 78 upwardly through cavity 66 to engage the underside of latch element 68 thereby projecting its forward tip 70 above the level of shelf 62. The upward projection of latch 68 is restricted by the engagement of its upper surface, rearwardly of depression 72, with the top surface of cavity 66.

With that structure of the apparatus having been detailed, a description of operation will now be set forth. In presenting this description, reference will be made to FIGURES 2 and 3A-D. FIGURE 2 diagrammatically illustrates the positions of a bearing 22 attached to the movable panel 10 as the latter is moved into operative relationship with the fixed panel 12. Since the tips of patchcords projecting through the movable panel 10 towards panel 12 are fixed with respect to bearings 22, FIGURES 3A-D diagrammatically illustrate the relative positions of a cord tip and its associated contact as the bearing 22 moves from positions A to D in FIGURE 2.

It will first be assumed that a number of patchcords are programmed with respect to the movable panel so that their tips project towards panel 12 on the opposite side of panel 10 from handles 20. To complete the contact assembly, panel 10 is lifted by handles 20 and is moved such that bearings 22 rest on shelves 62 of hangers 34, as illustrated in position A in FIGURE 2. In this position, the patchcord tips, represented by the single element 80, are horizontally and vertically spaced with respect to their associated contacts 28. This is shown in FIGURE 3A.

With the cam actuator in the position shown in FIGURE 1 wherein the fall portions of cams 40 face upwardly, the movable panel 10 is next manually rolled along shelves 62 towards panel 12. The forward surfaces of latch element projections 70 are inclined to permit the latch element 68 to be pivoted against the force of springs 74 as bearings 22 engage projections 70. The depression of elements 68 allows the bearings to pass over the projections into depressions 72. The force of springs 74 is sufficient to return the latch elements 68 to their original positions wherein the bearings are cradled in the position shown at B in FIGURE 2. It should be noted here that for convenience of illustration, the cam 40 in FIGURE 2 is shown in its final position D. When the bearings are in position B, the fall portions of cams 40 face upwardly such that the bottom of frame 14 of panel 10 is closely spaced therefrom. In position B, the patchcord tips 80 are positioned slightly below their associated contacts 28.

As the cam actuator 42 is moved from the position shown in FIGURE 1 towards housing 44, shaft 36 is rotated to actuate the cams 40. During the rise por-

tion of cam movement, the cams engage the underside of panel 10 to raise the bearings 22 from depressions 72 and project them into channels 64. Due to the incline of the channels, bearings 22 are lifted upwardly and inwardly in one direction towards panel 12. This results in patchcord tips 80 engaging their associated contacts 28 as the tips move upwardly and inwardly with respect to the contacts. The motion of tips 80 deflects the contacts 28 against their resiliency as well as causing relative longitudinal movement between the contacts and tips. Thus, there is a rubbing or wiping action between these two elements. This action has the effect of cleaning the elements.

In the position shown in FIGURE 3C, the contact 28 is at its maximum deflection. This has been caused by cam 40 reaching the completion of its rise thereby moving bearings 22 and pins 80 to their highest points, as well as to their closest relationship with panel 12. The bearings' position can be observed in FIGURE 2 at C.

The cam actuator 42 is mounted to shaft 36 such that the actuator is not received in housing 44 until the cams 40 have rolled past their maximum rise portions. Consequently, as the actuation of member 42 is completed, the panel 10 resting on cams 40 moves downwardly and away from panel 12 along channels 64 to a position shown at D in FIGURE 2. The corresponding positions of bearings 22 and cams 40 are also shown at their final positions in FIGURE 2. It is apparent that as panel 10 moves downwardly and away from panel 12, patchcord tips 80 tend to move down and away from their contacts 28 (FIGURE 3D). However, due to the resiliency of contacts 28, the physical connections between the tips and their contacts are maintained and a second wiping action occurs over the previously wiped area due to the relative longitudinal movement between the tips and the contacts. This results in an improved positive electrical connection free of foreign particles.

As the cam actuator 42 moves to its final position, spring detent 48 is projected into cavity 50 of the actuator to lock the actuator. Since the cams 40 have been rolled past their maximum rise portions during operation, the pressure of the resilient contacts 28 on the patchcord tips 80 tends to maintain the actuator 42 in its locked position. Accordingly, improved shock and vibration performance is achieved as the panels 10 and 12 are maintained in operative relationship.

The above-described embodiment is illustrative of a preferred embodiment of the invention but is not intended to limit the possibilities of insuring the features of improved positive contact and resistance to vibration or shocks. The contact assembly disclosed herein is an example of an arrangement in which the inventive features of this disclosure may be utilized, and it will become apparent to one skilled in the art that certain modifications may be made within the spirit of the invention as defined by the appended claims.

What is claimed is:

1. A multiple contact assembly for simultaneously completing a number of electrical circuits through the agency of patchcords being connected to a plurality of resilient contact elements, the assembly comprising:
  - a first panel member to which said contact elements are fixed and a second panel member which receives said patchcords;
  - a plurality of hanger elements joined to the inner side portions of said first panel member and projecting therefrom, said hangers being provided with upper surfaces extending from an area within the sides of the first panel member to points beyond said first panel member;
  - bearing members projecting from the outer side portions of said second panel member, said bearing members being positioned so as to permit the second panel member to rest on the upper surfaces of the hanger elements and to be moved at least par-

tially within the area defined by the sides of the first panel member into operative relationship with a cam;
means for actuating said cam to first produce relative movement between the panel members in one direction to bring said patchcords into engagement with the contact elements and to cause initial wiping of the contact elements and then to produce relative movement between the panels in the opposite direction to cause limited reverse wiping of the contacts.

2. A multiple contact assembly as set forth in claim 1, wherein the portions of the hanger elements within the inner side portions of the first panel member include inclined channels adapted to receive said bearing members when said cam is actuated to produce relative movement of the panel members, said channels thereby developing vertical and horizontal displacement of the patchcords with respect to the contact elements.

3. A multiple contact assembly as set forth in claim 1, further comprising means for locking said cam actuator to maintain the patchcords in engagement with the contacts.

4. A multiple contact assembly as set forth in claim 1, wherein said hanger elements includes a latching arrangement for positioning the panel on said hanger elements prior to the actuation of said cam member.

5

10

15

20

25

5. A multiple contact assembly as set forth in claim 1, wherein said cam member includes rise and fall portions, said cam actuator being displaced to first present an increasing cam rise portion to produce the relative movement of the panels in the one direction and then to pass a position of maximum cam rise and move towards said fall portion thereby producing the relative movement of the panels in the opposite direction.
